UNITED STATES PATENT OFFICE.

ROBERT E. L. JANNEY, OF CHICAGO, ILLINOIS, ASSIGNOR TO AMERICAN STEEL
FOUNDRIES, OF NEW YORK, N. Y., A CORPORATION OF NEW JERSEY.

COUPLING.

1,325,518.

Specification of Letters Patent. Patented Dec. 23, 1919.

Application filed August 9, 1916. Serial No. 113,876.

To all whom it may concern:

Be it known that I, ROBERT E. L. JANNEY, a citizen of the United States, and resident of Chicago, in the county of Cook and 5 State of Illinois, have invented certain new and useful Improvements in Couplings, of which the following is a specification.

My invention relates to car couplings and has particular reference to a novel lock support designed to prevent the lock from occupying an inoperative position.

In car couplers of the type employing a vertically moving block lock it is common to employ a lifting link, the link being movable relative to the lock, a portion of the lifter underlying a shoulder or abutment on the coupler in the normal inactive position of the parts and thereby acting as an anti-creep provision. In a coupler of a certain 20 type also it is found desirable to support the lock when in its lowermost position on the knuckle thrower. It has been found that in event the knuckle thrower becomes broken and the support for the lock thereby 25 moved, the lock has a tendency to tilt in its lowermost position and to lie in such relation to the wall surrounding the throat of the coupler that the lock cannot be lifted; furthermore, when the lock has descended 30 to the lower position permitted by the displacement of the support therefor the lifting link is quite likely to become disengaged from the lock.

The same difficulties, to a greater or less 35 extent, are present in the operation of the same coupler by means of the bottom lift or operating device. To overcome the objections heretofore referred to, I provide a lug or support located at one of two points 40 within the coupler head, and which supports do not normally contact the lock or have any function, becoming active only upon the breakage or removal of the lock-supporting device.

45 The invention will be more readily understood by reference to the accompanying drawings, wherein—

Figure 1 is a fragmentary longitudinal section through a car coupler constructed in 50 accordance with my invention;

Fig. 2 is a sectional view on the irregular line 2—2 of Fig. 1, the knuckle thrower being omitted;

Fig. 3 is a detail fragmentary horizontal

sectional view taken on the line 3—3 of 55 Fig. 1.

Fig. 4 is a view similar to Fig. 1 showing a further adaptation of the invention, and

Fig. 5 is a sectional view on the line 4—4 of Fig. 4. 60

Referring more particularly to the drawings, it will be seen that the coupler head 10 provides an inner cavity within which a lock is mounted, the lock comprising a block portion 11, having a fulcrum lug 12 and a 65 depending foot 13. A notch 14 in this foot or leg provides for lock setting engagement with the knuckle thrower shown in section at 15, in Fig. 1 only. The extreme lower end of the leg 13 is provided with an inclined slot 16, which is engaged by the bottom throwing or lifting arrangement. The upper portion of the lock is provided with an inclined, undercut groove 17, with which 70 trunnions 18 on the top lifter or link 19 engage, said lifter projecting downwardly through an opening in the top wall of the coupler. The lifter at its lower end is provided with a notch 20, which engages with a shoulder or abutment 21 on the back wall 75 of the coupler. The lower or inclined portion of the notch acts as an anti-creep provision, preventing the upward movement of the lock until the lifter is moved out from under the projection or ledge 21, as occurs 80 during the first lifting action of the link. The vertical portion of the notch which lies against the back wall serves to prevent the disengagement of the lifter from the lock, 85 as would be permitted if the lock were allowed to drop a distance sufficient to permit the lower end of the lifter to pass beneath the ledge 21. The lifter may be disconnected 90 from the lock by a downward and rearward relative movement with respect thereto. 95

As best shown in Fig. 3 of the drawings, it will be seen that the fulcrum lug 12 and that part of the front of the locking block 11 from which the fulcrum lug projects is of less width than the entire locking block, thereby providing an upright shoulder 26 which bears against a part 27 of the internal front wall of the coupler head when the locking block is on the knuckle thrower 15, as shown in Fig. 1, thereby to prevent the lock 100 from tilting forwardly into an inoperative position. As indicated by a dotted line in Fig. 1, it will be seen that the upright shoul- 105

der 26 on the locking block extends the full height or depth of the latter so as to insure a proper engagement of the shoulder with the front wall of the coupler head in all normal positions of the locking block.

To obviate the difficulties such as would follow the dropping of the lock due to a breakage of the knuckle thrower 15, I provide a ledge or lug 22, located on the guard 10 arm side of the coupler and preferably at a point just beneath the normal lowered position of the lock. In the absence of the lugs 22 and in event of the breakage of the knuckle thrower, the lock drops until the 15 portion thereof which is shown as resting on the knuckle thrower rests upon the floor 23 of the coupler, in which position the forward upper end of the lock would underlie the wall surrounding the throat opening of 20 the coupler and would become jammed therein as soon as the lock was sought to be lifted.

It will, of course, be understood that when the locking block 11 is supported on the 25 ledge or lug 22, the shoulder 26 at the front of the locking block 11 remains in engagement with the part 27 of the front of the coupler head so as to prevent the locking block from tilting forwardly and becoming 30 jammed in the throat opening of the coupler head.

In the construction shown in Figs. 4 and 5 much the same result is obtained as far as the elimination of the possibility of jamming is concerned. In that case the lock may be allowed to drop, due to breakage of the knuckle thrower, until it rests upon the floor of the coupler. I have, however, provided a lug 24, which projects upwardly 40 into the throat opening from the guard arm side of the head and serves to maintain the lock in the tilted position shown, which prevents the lock from assuming such position as will cause it to jam in the manner described. In the locked position of the locking block, in the construction shown in Figs. 4 and 5, the shoulder 26 on the block of course engages the part 27 of the coupler head, as shown in Fig. 1 of the drawings, so 45 as to prevent the locking block from tilting forwardly into an inoperative position. Of course, when the support, afforded by the knuckle thrower, is removed from beneath the locking block, the latter drops to the position shown in Fig. 4 of the drawings, and of course the shoulder 26 of the locking block becomes disengaged from the part 27 of the front wall of the coupler head, and if it were not for the lug 24, the locking block 50 would tilt forwardly into the opening in the throat of the coupler head and would become jammed therein by any attempt to lift the locking block by means of the lifter.

It will be understood, of course that the

actions which have been referred to relate 65 to such actions as occur or are possible in the closed position of the knuckle. Of course, the only manner in which the parts may be assembled is by reason of their assuming, during the absence of the knuckle, 70 the positions which, in the presence of the knuckle, are described as impossible as the result of my improvements.

In a coupler head provided with either embodiment of the invention, the locking 75 block is insertible and removable through the throat opening in the coupler head and through which the knuckle tail enters.

To enable the ready insertion and removal of the lock in the absence of the knuckle, I 80 cut away a portion of the width of the foot of the lock, thereby leaving a space which I have lettered 25 in Figs. 2 and 5. This permits the lock to be tilted an amount sufficient to free it from either of the lugs 22 or 24. 85

Obviously, therefore, the invention contemplates means which are normally inactive, but which become active upon the breakage or removal of any parts, to prevent the lock from occupying such position 90 as will cause it to become inoperative and modifications of the invention which include features such as described are considered within the scope of my invention. 95

I claim:

1. In a coupler, the combination of a lock of the vertically moving type, a movable support for the lock when in its normal position, and means for preventing forward tilting of the lock including a lug carried by and projecting laterally from the guard arm side of the head, said lug being located in such position as to partially support said lock upon failure of the said movable support, whereby said lock is prevented from assuming such a position as will permit of its becoming jammed. 100

2. In a coupler, the combination of a head having a throat opening, a vertically moving block lock, a movable support for said lock when in its normal position, in which position the lock extends above said throat opening and the arrangement being such that in the absence of said movable support said lock may drop and tilt forwardly to assume a position in which the upper forward corner thereof lies in said throat, and means in the form of a lug carried by and projecting from the guard arm side of the head preventing said lock from assuming 115 such position, substantially as described. 120

Signed at Chicago, Illinois, this 5th day of August, A. D. 1916.

ROBERT E. L. JANNEY.
